UNITED STATES PATENT OFFICE.

DONALD ROBERTSON AND RICHARD MIDDLETON SIMPSON, OF WELLINGTON, NEW ZEALAND, ASSIGNOR TO IMPERIAL POSTMARKERS LIMITED, OF WELLINGTON, NEW ZEALAND, AN INCORPORATED COMPANY OF NEW ZEALAND.

MAIL-MARKING MACHINE.

1,386,952.

Specification of Letters Patent. Patented Aug. 9, 1921.

Application filed January 23, 1920. Serial No. 353,641.

To all whom it may concern:

Be it known that we, DONALD ROBERTSON and RICHARD MIDDLETON SIMPSON, both citizens of the British Empire, residing at #13

5 Talavera Terrace and 5 Upland road, Wellington, Dominion of New Zealand, have invented a new and useful Mail-Marking Machine, of which the following is a specification.

10 This invention relates to machines for canceling the stamps on mail matter and printing the name of a post office the date and other particulars thereon. It can also with obvious adaptations be used for printing on envelopes leaflets and such like.

The object of the invention is to provide a machine of the type referred to simple and cheap in construction and with a minimum of parts.

20 The invention consists in the features and combinations and arrangements of parts hereinafter described and more particularly pointed out in the claims. In the accompanying drawings embodying the invention 25 Figure 1 is a perspective view of the machine, Fig. 2 is a perspective view of the machine with the top plate removed to show the working parts, Fig. 3 is a top view enlarged of the improved separator and 30 Fig. 4 is a back view of the improved separator.

The machine as illustrated is driven by hand but can be driven by power by obvious adaptations.

35 The horizontal driving wheel (1) is made preferably heavy and revolves on an axle (2) secured to the frame (4). A cap (5) screws into the top of the axle (2) and holds the wheel thereon.

40 Around the upper part of the periphery of the driving wheel (1) there is a rubber feeding band (6) kept in place by its elasticity. The lower part of the driving wheel is provided with two grooves an upper one

45 (7) and a lower one (8) for two endless driving belts (9,10). A handle (11) is provided on the wheel to rotate it by hand. The upper belt (9) runs directly around a pulley (12) revolving on a spindle (13) secured to the frame (4). Two stacking wheels (14,15) 50 provided with curved arms (16) and integral with a sleeve (17) between them are secured

to the spindle (13) by the sleeve being placed thereon and a screw cap (18) screwing into the end of the spindle (13). The lower belt (10) runs tangentially to a small guide pulley (19) rotatably mounted on one end (20^a) of a bent lever (20) which is pivotally mounted on a spindle (21) secured to the frame (4) and at the top of which spindle (21) is rotatably mounted a central larger pulley (22) around which the lower belt (10) runs. Next and adjacent to the central large pulley (22) is the marking wheel spindle (23) secured to the other end (20^b) of the bent lever (20) and having on it a sleeve carrying at its lower end and nearly tangential to the central pulley (22) a small pulley (24) around which the lower belt (10) runs and thence back to the lower groove (8) on the driving wheel (1). The ends of the bent lever (20) are moved backward and forward on its pivot (21) by a rod (25) which is threaded and rotates in a plumber block (26) secured near the edge 75 of the frame (4) and extends outside thereof terminating in a button (27) adapted to turn it. The inner end (28) of the rod (25) is threaded and engages a threaded hole in a sliding piece (29^a) which slides in brackets 80 (29) secured to the frame (4). The inner end (30) of this sliding piece (28) is kept in contact with the free end (20^a) of the bent lever (20) by a helical spring (31) whose ends are secured respectively to the 85 sliding piece (28) and to the free end (20^a) of the bent lever (20) near the central pulley (22). By this arrangement the marking wheel is caused to coöperate with the lower portion of the horizontal driving 90 wheel as closely as desired and simultaneously the belt (10) is tensioned correspondingly.

An arm (32) has one end pivoted by a pivot (33) to the frame (4) and has secured to its other end the inking wheel spindle (34). On the arm (32) near the inking wheel spindle (34) one end of a helical spring (35) is secured, the other end of the spring being secured to the bent lever (20) 95 between the marking wheel spindle (23) and the central pulley (22). By this arrangement the inking wheel is kept in yielding contact with the marking wheel. 100

There is a top cover plate (36) provided with openings for the marking wheel spindle (23) and the inking wheel spindle (34) and is secured by screws (37) to the frame 4. 5 To this top plate (36) is secured a vertical fence or guard (38) at one edge thereof and a vertical curved guard fence (39) provided with an opening (40) to allow of the operation therethrough of part of the rubber band 10 (6) on the driving wheel (1). Between the curved guard fence (39) and the edge fence (38) is a vertically slideable gate (41) provided with two horizontal slots (42, 43) where- 15 through the curved arms (16) of the two stacking wheels (14, 15) project for opera- 20 tive purposes. A marking wheel (44) is placed on the marking wheel spindle (23) and is supported by a circular ledge (46) formed thereon so as to clear the surface of the top plate (36).

An inking wheel (47) is placed on the inking wheel spindle (34) and is supported by a circular ledge (48) formed thereon so as to clear the surface of the top plate (36). 25 The separator Fig. 3 is adjustably secured by a nut and screw (49) to the top plate with its face at an acute angle with the rubber band (6) and nearly touching same.

30 This separator consists of a frame 50 having a bracket (51) provided with a slot (52) for securing same adjustably by means of the nut and screw (49) to the top plate (36) as before described. The separator has 35 a hinged finger end portion (53) hinged by the hinge pin (65) to the frame, its ends being connected by a detachable rod (54) having on it a rubber sleeve (55). The whole frame in plan is a flattened C. The 40 other ends (56) of the frame are connected by a rod (57) which has on it a rubber sleeve (58). In notches (59) at the back of the frame and near the ends (56) a detachable rod (60) rests. A series of parallel rubber bands (61) are placed with 45 their ends around the detachable rods (54, 60) and extend in a chord across the front of the C shaped frame presenting a flat surface broken by spaces (62) separating 50 the bands. A curved guard (63) is adjustably secured by a wing nut (64) and bolt to the top plate (36) and serves to prevent ink 55 splashing off the inking wheel (47) and letters from being caught and crumpled between that wheel and the marking wheel (44).

In operation letters placed on edge in bunches are fed by hand against the rubber band (6) and are carried against the rubber 60 bands of the separator, the hinged finger of which yields periodically and allows a letter to pass and be carried on by and between the rubber band (7) and the marking wheel whereby they are marked by suitable type on the wheel and are thence car-

ried by their momentum and stopped by the edge fence coming under the operation of the curved arms of the stacking wheel, and being stacked in front of each other their edges resting against the edge fence. 70

We claim—

1. A revoluble platen element, a marking wheel mounted for rotation and for movement toward and from the platen element, an endless band connecting said 75 platen element and said marking wheel, a tightener for said band, and means to simultaneously shift the marking wheel and tightener, to cause the latter to increase the tension of the endless band as the marking wheel is moved toward the platen element. 80

2. In a mail marking machine a bent lever, a guide pulley mounted at one end, a spindle secured to the other end, a second pulley on said spindle provided with a sleeve for a marking wheel and a third central pulley mounted on said bent lever between said guide pulley and said second pulley substantially as and for the purposes set forth. 90

3. In a mail marking machine a frame, a driving wheel mounted on said frame, a bent lever pivotally mounted on said frame, a guide pulley on one end of said bent lever, 95 a spindle mounted on the other end of said bent lever, a sleeve carrying pulley on the lower end of said spindle, a marking wheel on said sleeve, a central pulley mounted on said bent lever between said guide pulley and said sleeve carrying pulley and an endless driving belt running around said driving wheel, said guide pulley, said central pulley and said sleeve carrying pulley substantially as described. 100

4. In a mail marking machine a frame, a driving wheel mounted on said frame, a bent lever pivotally mounted on said frame, a guide pulley on one end of said bent lever, 110 a spindle mounted on the other end of said bent lever, a sleeve carrying pulley on the lower end of said spindle, a marking wheel on said sleeve, a central grooved pulley mounted on said bent lever between said guide pulley and said sleeve carrying pulley, an endless driving belt running around said driving wheel, said guide pulley, said central pulley and said sleeve carrying pulley and means for moving said bent lever whereby said marking wheel is brought into desired coöperation with said driving wheel and simultaneously said guide pulley correspondingly adjusts the tension of said driving belt substantially as described. 115

5. In a mail marking machine a bent 125 lever, a guide pulley mounted at one end, a spindle secured to the other end, a second pulley on said spindle provided with a sleeve for a marking wheel and a third central pulley mounted on said bent lever be- 130

tween said guide pulley and second pulley, and means for inking said marking wheel substantially as and for the purposes set forth.

- 5 6. A mail marking machine comprising a driving wheel, a marking wheel coöperating with said driving wheel, a driving belt between said driving wheel and said marking wheel rotating said marking wheel, adjusting means for keeping said marking wheel in coöperation with said driving wheel and simultaneously tensioning said driving belt substantially as described.
